CLAIM

The ornamental design for a buffing pad, as shown and described.

DESCRIPTION

FIG. 1 is a top perspective view of a buffing pad in accordance with the invention;

FIG. 2 is a bottom perspective view of the buffing pad shown in FIG. 1;

FIG. 3 is a top view of the buffing pad shown in FIG. 1; FIG. 4 is a bottom view of the buffing pad shown in FIG. 1; FIG. 5 is a left side view of the buffing pad shown in FIG. 1;

FIG. 6 is a right side view of the buffing pad shown in FIG. 1; FIG. 7 is a front side view of the buffing pad shown in FIG. 1; and,

FIG. 8 is a back side view of the buffing pad shown in FIG. 1.

(Continued)

The dash-dash broken lines are included for the purpose of illustrating portions of the buffing pad and forms no part of the claimed design.
